DESIGN FOR A REFRACTING BOWL FOR DIRECT LIGHTING LUMINAIRES

Kurt Franck, Newark, Ohio, assignor to Holophane Company, Inc., New York, N. Y., a corporation of Delaware

Application October 10, 1940, Serial No. 95,751

Term of patent 14 years

To all whom it may concern:

Be it known that I, Kurt Franck, a citizen of the United States of America and a resident of Newark, in the county of Licking and State of Ohio, have invented a new, original, and ornamental Design for a Refracting Bowl for Direct Lighting Luminaires, of which the following is a specification, reference being had to the accompanying drawing, forming a part hereof.

In the drawing, the single figure is a perspective view of the refracting bowl for direct lighting luminaires taken from underneath and showing my new design.

I claim:

The ornamental design for a refracting bowl for direct lighting luminaires, as shown.

KURT FRANCK.
